UNITED STATES PATENT OFFICE.

RUTH A. GILCHRIST, OF WILKES-BARRÉ, PENNSYLVANIA.

DESIGN FOR A LINING FOR PRESERVE-JAR COVERS.

SPECIFICATION forming part of Design No. 24,337, dated May 28, 1895.

Application filed April 12, 1895. Serial No. 545,533. Term of patent 14 years.

To all whom it may concern:

Be it known that I, RUTH A. GILCHRIST, a citizen of the United States, residing at Wilkes-Barré, in the county of Luzerne and State of Pennsylvania, have invented and produced a new and original Design for Linings for Preserve-Jar Covers; and I do hereby declare the following to be a full, clear, and exact description of the same, reference being had to the accompanying drawings, forming a part thereof.

Figure 1 is a perspective view of a lining for fruit-jar covers, exhibiting my design; and Fig. 2 is a vertical sectional view of the same. The leading feature of my design consists of a pendant of approximately cone or semi oval form and having a horizontal rim extend-

ing out beyond the largest diameter or base of the pendant.

A in the drawings represents the cone or semi oval periphery; B, the horizontal rim; C, a hollow in the pendant. The horizontal rim may be provided on its peripheral edge with a beveled or rounded surface D.

What I claim is—

The design for a lining for a fruit jar cover, substantially as shown and described.

In testimony whereof I hereunto affix my signature in presence of two witnesses.

RUTH A. GILCHRIST.

Witnesses:

JOHN STURDEVANT,
P. F. LYNCH.
